UNITED STATES PATENT OFFICE.

WALTER F. KASPER, OF FAIRMONT, MINNESOTA, ASSIGNOR TO FAIRMONT RAILWAY MOTORS, INC., OF FAIRMONT, MINNESOTA, A CORPORATION OF MINNESOTA.

CONDENSER FOR WATER-COOLED ENGINES.

Application filed August 13, 1924. Serial No. 731,778.

This invention relates to improvements in condensers for water-cooled or internal combustion engines, and more particularly relates to such condensers adapted for use in 5 conjunction with the usual hopper or tank of a railway motor car engine.

The particular object of this invention is to provide a device, which, when operatively connected to the hopper of the engine, 10 will cause the steam generated therein to be cooled and condensed to water, and thereafter returned to the engine hopper, thereby permitting the engine to be run for a long period of time without the necessity 15 of having to add additional water to the hopper or engine cooling system from outside sources.

A further and more specific object of the invention is to provide such a device having 20 a water-seal or trap interposed between the engine hopper and the condenser, which functions to cause the steam generated in the hopper to be intermittently delivered to the condenser, thereby allowing the condenser 25 to substantially cool between each charge of steam thereinto, resulting in a more perfect and thorough condensation of the steam.

A further object of the invention is to 30 provide a condenser of simple and inexpensive construction, which will readily lend itself for use in connection with the cooling systems of ordinary water cooled engines such as are commonly employed in railway 35 motor cars, automobiles, trucks, etc.

Other objects of the invention will more 40 fully appear from the following description and the accompanying drawings and will be pointed out in the annexed claims.

In the drawings there has been disclosed 45 a structure designed to carry out the various objects of the invention but it is to be understood that the invention is not confined to the exact features shown as various changes may be made within the scope of the claims which follow.

In the accompanying drawings forming a part of this specification,

Figure 1 is a sectional elevation of a portion 50 of a railway motor car showing my invention applied to the engine hopper thereof; and

Figure 2 is a diagrammatic representation of an engine hopper and condenser in

section, showing the water-seal or trap interposed therebetween.

In the selected embodiment of the invention here shown there is illustrated, for purposes of disclosure, a conventional type of railway motor car, comprising the usual frame 4, axle 5, carrying wheels 6, engine 7 and the engine hopper 8. The usual operator's platform 9 is shown arranged in the usual manner over the engine and hopper.

An important feature of this invention 65 resides in the novel means provided for cooling and condensing the steam generated within the engine hopper, and returning it thereto in the form of water. Such means consists in the provision of a condenser 11 70 preferably mounted adjacent the forward end of the car and supported by suitable means such as the upright supporting members 12. The form of condenser here shown comprises upper and lower chambers 13 and 14, respectively, as particularly shown in Figure 2. These chambers are in communication with each other through a series of upright tubes 15 interposed therebetween. A filler opening 16 is provided in the upper 75 wall of the chamber 13 for the introduction therein of a suitable cooling medium such as water, and this opening is preferably closed by means of a cap 17. A vent pipe 18 is provided in the upper chamber 13 and 80 this pipe also functions as an overflow pipe, should the cooling system be filled too full of water. From the foregoing, therefore, it will be seen that the condenser here shown 85 is similar in construction to an ordinary water-cooling radiator, such as are commonly used in conjunction with internal combustion engines.

The form of hopper here shown is of this 90 type commonly used on railway motor car 95 engines. As shown, the engine cylinder 19 is mounted in the lower portion of the hopper so as to be substantially surrounded by the water or other cooling medium 20. A steam chamber 21 is provided above the 100 normal water level of the hopper. A pipe section 22 is suitably secured to the upper portion of the hopper and outwardly and downwardly leads therefrom and has its other end connected to a water-seal or trap 105 preferably located at a point below the normal water level of the hopper. This trap 110 preferably consists of a horizontal pipe sec-

tion 23 having one end connected to the horizontal end portion 24 of the pipe 22, and its other end connected to a curved pipe 25 which upwardly leads therefrom and has its other end connected to the lower chamber 14 of the condenser, preferably at one end thereof, thereby establishing communication between the hopper and the condenser. Thus, by arranging the horizontal 10 pipe section 23 below the level of the water in the hopper it will normally be filled with water as shown in Figure 2, thereby normally sealing the hopper 8 from the condenser 11.

15 A nipple 26 is secured to the opposite end portion of the lower chamber 14, and has one end of a return pipe 27 connected thereto which downwardly leads therefrom and has its other end connected to a similar nipple 28, secured to the lower portion of the hopper 8. The pipe sections 23 and 27 are preferably of flexible material so that the condenser may be secured firmly to the motor car frame and still permit the engine 20 to be moved back and forth on the usual sliding base provided for that purpose, in tightening or loosening the belt which drives the car or other shaft which the engine may be belted to.

30 In the operation of this novel device, in conjunction with an internal combustion engine, steam is generated in the steam chamber 21 above the normal water level of the hopper. When the steam pressure rises

35 above a certain point, the water in the trap will be upwardly forced into the condenser, thereby allowing the steam to surge into the condenser and entirely fill the interior thereof. As the steam contacts with the substantially cool walls of the chambers 13 and 14, and the tubes 15, it is immediately cooled and condensed to water. When the pressure in the hopper and the condenser is equalized, the water returns to the trap or pipe section 40

23 thus sealing the hopper from the condenser with the result that steam does not then pass to the condenser but is confined in the steam chamber 21 of the hopper until the predetermined pressure is again built up.

45 Thus it will be seen that the steam is intermittently delivered to the condenser, which, in actual operation, has been found to result in more perfect and thorough condensation of the steam.

50 The form of condenser employed is preferably of the open type so that a current of air may be directed therethrough for cooling the walls thereof. When used with a stationary engine, a fan is preferably provided for drawing cold air through the condenser; but when used in connection with a railway motor car engine and the like, the use of a fan is unnecessary. However, should it be necessary to run an engine for 55 a long period at slow speed then it is ad-

visable to use a fan to draw air through the condenser.

In filling this novel cooling system with water or other cooling medium, no particular care need be taken, provided, of course, a sufficient quantity is introduced thereinto to cause the trap to function. Should too much water be introduced or should the system be completely filled before starting the engine; then, as the engine heats the water 70 it will expand and a portion thereof will overflow through the vent pipe 18. When the water reaches the boiling point and steam is generated, the surplus water will be discharged through the vent pipe in the 75 form of steam or water until the proper level is reached, after which the system will continue to function as long as the engine is in operation, the steam being intermittently delivered to the condenser where it will be 80 cooled and condensed to water, after which it will return to the trap with the resultant sealing of the hopper from the condenser.

By thus intermittently delivering the steam to the condenser from the hopper, the 85 walls of the chambers 13 and 14, and also of the tubes 15 of the condenser, will be substantially cooled between each charge of steam thereinto, thereby causing the steam to be more quickly condensed to water than 90 would be possible if the trap were not used and the steam allowed to constantly flow or rise into the condenser.

95 I claim as my invention:

1. An apparatus of the class described 100 comprising a gas engine cylinder, a hopper enclosing said cylinder and adapted to contain a cooling fluid wherein said cylinder is immersed, a condenser, a pipe leading from the upper portion of said hopper above the 105 level of the cooling fluid and having a trap connection with said condenser, and a return pipe leading from said condenser to the lower portion of said hopper.

2. The combination with a gas engine cylinder and a hopper containing a cooling fluid wherein said cylinder is immersed, the upper portion of said hopper having a steam chamber above the level of the fluid, of a condenser, a pipe leading outwardly and 110 downwardly from said steam chamber and having a water-trap connection with the lower portion of said condenser, and a return pipe leading from said condenser into the lower portion of said hopper, the liquid 115 in said trap being periodically forced into said condenser by the accumulation of pressure in said chamber and allowing such pressure to flow into said condenser.

3. In a liquid circulating system, a heater chamber, a condenser, and circulating conduit connections therebetween, including a liquid trap in one of the connections, said chamber being partially filled with liquid to provide a steam space, whereby steam gen- 125 130

erated in the chamber will force the trap liquid and steam into said condenser and return the water of condensation to reform said trap.

5. 4. In a device of the class described, a heater chamber, a condenser, a conduit connecting the top of the chamber with the bottom of the condenser, said conduit having a water trap below the level of the con-

denser, said chamber having liquid therein 10 normally, maintained substantially at a level with the bottom of the condenser, and a return conduit from the condenser to the chamber.

In witness whereof, I have hereunto set 15 my hand this 8th day of August, 1924.

WALTER F. KASPER.
